HAND GRENADE

George Cardini, New York, N. Y., and Warren H. Davis, Nashua, N. H.; said Davis assignor to Charles L. Fish, Pepperell, Mass., trustee, and said Cardini assignor of sixty-six and two-thirds percent of his share to Anthony A. Calandra, Newark, N. J., trustee

Application February 24, 1941, Serial No. 380,196

9 Claims. (Cl. 102—64)

This invention is directed to improvements in a hand grenade of the contact explosion type. The improved hand grenade comprises, generally, a casing, two explosive containers and detonating devices carried thereby, said containers being brought into cooperation to explode the detonators and thereby the grenade by the impact of any part of the hand grenade with an object.

The hand grenade comprises, more specifically, a casing and two explosive containers which are movable endwise and/or tiltable in the casing, said containers having firing tubes bearing percussion caps and firing pins, which firing pins are moved endwise to explode the caps and thereby the grenade by an endwise and/or tilting movement of the containers due to the impact of any part of the grenade with an object.

A double lock may be provided for the hand grenade to permit the grenade to be safely handled. This double lock in the present instance is shown as comprising a flight removable lock for loosely holding the containers against explosion and a manually removable lock for the flight removable lock.

In the drawings:

Fig. 1 represents a top plan view of the hand grenade with the parts in their assembled and locked positions.

Fig. 2 represents a side elevation of the same.

Fig. 3 represents a bottom plan view of the same.

Fig. 4 represents a cross section taken in the plane of the line IV—IV of Fig. 2.

Fig. 5 represents a longitudinal central section taken in the plane of the line V—V of Fig. 2.

Fig. 6 represents a cross section of the grenade showing the two locks removed therefrom.

Fig. 7 represents the positions which the parts assume when the side of the grenade strikes an object to explode the grenade.

Fig. 8 represents the positions of the parts when an end of the grenade strikes an object to explode the grenade.

The hand grenade casing may be constructed of suitable material, as sheet metal, and it is shown as comprising a cylindrical portion 1 and removable tapered end portions 2.

The two explosive containers 3 may be of suitable material, as cast iron or steel, scored along their inner and outer surfaces as shown at 4 to increase their fragmentation when exploded. Each of these containers has a filling hole for the explosive 5, which hole is closed by a plug 6.

The detonating means for exploding the con-

tainers irrespective of the position which the grenade assumes when it strikes an object, will now be described.

Firing tubes 7 may be provided with heads 8 which have screw-threaded engagements with their respective central openings through the bases of the explosive containers 3. The outer ends of these firing tubes 7 open into the space between the bases of the containers and the inner ends of these firing tubes are open to the explosive 5 within the containers. These firing tubes are shown as having interior annular shoulders 9 for seating the percussion caps 10.

Firing pins 11 for detonating the percussion caps 10 are freely slideable in the firing tubes 7. These firing pins 11 are shown as provided with heads 12 located opposite each other in the space between the explosive containers 3.

The double lock for the hand grenade may comprise the following devices: The flight removable lock which normally holds both of the containers against explosive movement in the casing is shown as comprising two curved wings 13 hinged to forked bars 14, 15 which embrace the firing pins 11 between the heads 12 and the bases of the containers 3. The cylindrical portion 1 of the casing has a side wall opening 16 through which the flight removable forked bars 14, 15 extend. The wings 13 may be provided along their curved edges with narrow flanges 17 which overlap exterior annular shoulders 18 on the end portions of the casing, to hold the wings against longitudinal displacement when locked to the casing.

These wings 13, when folded, snugly embrace the cylindrical portion 1 of the casing and their free ends are held together by a manually removable lock which is shown as a double pronged pin 19 having a tab 20. The prongs of the pin are normally spread apart and must be forced toward each other to pass through the holes 21 in the free ends of the wings 13 and also through holes 22 in the casing on opposite sides of the opening 16 therein.

The endwise movement of the explosive containers 3 is provided for by spacing the containers a short distance apart so that when the grenade strikes an object endwise, the one or the other of the containers will move endwise to cause the firing pins to explode the caps and thereby the containers.

The tilting movement of the explosive containers 3 is provided for by interior annular shoulders 23 on the end portions 2 of the casing, which shoulders engage and coact with exterior

tapered annular shoulders 24 on the containers, to cause the containers to tilt toward each other to move the firing pins to explode the caps and thereby the containers when the side of the grenade strikes an object.

In assembling the hand grenade the firing tubes 7 are secured in their containers 3 with the percussion caps seated in the tubes against the shoulders 9. The containers may be supplied with the desired explosive 5 and the plug 6 then used to close the filling holes. The firing pins 11 are inserted into the tubes 7. The containers are placed within their respective end portions of the casing with the exposed heads 12 of the firing pins located opposite each other in the space between the containers. The casing members 1 and 2 may then be secured together.

The forked bars 14, 15 of the flight removable lock may then be passed through the side wall opening 16 in the casing to embrace their respective firing pins between the heads 12 and the bases of the containers to prevent explosive movement of the containers. The wings 13 may then be folded around the cylindrical portion 1 of the casing.

With the parts thus assembled, the manually removable lock for the flight removable lock is then attached by forcing the two prongs of the pin 19 toward each other and passing them through the holes 21 in the wings and the holes 22 in the side wall of the casing.

With the parts thus assembled and locked the grenade may be handled with complete safety.

When it is desired to use the grenade the pin 19 of the manually removable lock may be withdrawn by means of the tab 20. The grenade may then be thrown at the desired object. As the grenade passes through the air the action of the air on the wings of the flight removable lock will cause the wings to spread and remove the forked bars from the grenade. This action will release the containers and firing pins so that when the grenade strikes its object the containers are caused to move endwise and/or tilt toward each other according to what part of the grenade strikes its object, to cause the firing pins to simultaneously detonate the percussion caps and thereby explode the containers.

It will thus be seen that the explosion of the grenade is ensured irrespective of the position of the grenade when it strikes its object. It will also be seen that the hand grenade when not in use is safe to handle and transport. The grenade is simple in construction, reliable in action, inexpensive to manufacture, and can be readily removable.

It is evident that various changes may be resorted to in the construction, form and arrangement of the several parts without departing from the spirit and scope of this invention.

What is claimed is:

1. In a hand grenade, a casing comprising a cylindrical portion and two removable tapered end portions, two separated tapered explosive containers, detonators therefor comprising tubes secured to the bases of the containers in line with each other, said tubes extending into the containers and open to the interiors thereof, the outer ends of the tubes being open to the space between the containers, percussion caps seated in said tubes at a distance from their open outer ends, and firing pins slidable in the tubes, said firing pins having heads opposite each other in said space between the containers, a flight re-

movable lock comprising bars located between the said heads of the pins and the bases of the containers and wings hinged to said bars, the bars serving to hold the heads of the pins in contact with each other and the containers against explosive movement in the casing, and a manually removable lock for said flight removable lock.

2. In a hand grenade, a casing, two endwise movable and tilttable separated explosive containers enclosed thereby, detonators for the containers, each detonator including a percussion cap and a slidable firing pin therefor projecting into the space between the containers in position to coact with the other firing pin by the end or side impact of the grenade with an object, to explode the containers, coacting means between the containers and the casing for causing the containers to tilt toward each other by the side impact of the grenade, and a flight removable lock for holding the containers against endwise and tilting movement within the casing.

3. In a hand grenade, a casing, two endwise movable and tilttable separated explosive containers enclosed thereby, detonators for the containers, each detonator including a percussion cap and a slidable firing pin therefor projecting into the space between the containers in position to coact with the other firing pin by the end or side impact of the grenade with an object, to explode the containers, coacting means between the containers and the casing for causing the containers to tilt toward each other by the side impact of the grenade, a flight removable lock for holding the containers against endwise and tilting movement within the casing, and a manually releasable lock for the flight removable lock.

4. In a hand grenade, a casing, two endwise movable and tilttable separated explosive containers enclosed thereby, detonators for the containers, each detonator including a percussion cap and a slidable firing pin therefor projecting into the space between said containers in position to coact with the other firing pin by end or side impact of the grenade with an object, to explode the containers, interior and exterior shoulders on the casing and containers respectively to cause the containers to tilt toward each other by the side impact of the grenade, and a flight removable lock for holding the containers against endwise and tilting movement within the casing.

5. In a hand grenade, a casing, two endwise movable and tilttable separated explosive containers enclosed thereby, detonators for the containers, each detonator including a percussion cap and a slidable firing pin therefor projecting into the space between said containers in position to coact with the other firing pin by end or side impact of the grenade with an object, to explode the containers, interior and exterior shoulders on the casing and containers respectively, to cause the containers to tilt toward each other by the side impact of the grenade, a flight removable lock for holding the containers against endwise and tilting movement within the casing, and a manually releasable lock for the flight removable lock.

6. In a hand grenade, a casing, two endwise movable and tilttable separated explosive containers enclosed thereby, detonators carried by the containers, each detonator including a tube open to the interior of its container and to the space between the containers, a percussion cap

seated in the tube and a firing pin slidable in the tube and projecting into the space between said containers in position to coact with the other firing pin by the end or side impact of the grenade with an object, coacting means between the casing and containers to cause the containers to tilt toward each other by the side impact of the grenade, and a flight removable lock for holding the containers against endwise and tilting movement within the casing.

7. In a hand grenade, a casing, two endwise movable and tiltable separated explosive containers enclosed thereby, detonators carried by the containers, each detonator including a tube open to the interior of its container and to the space between the containers, a percussion cap seated in the tube and a firing pin slidable in the tube and projecting into the space between said containers in position to coact with the other firing pin by the end or side impact of the grenade with an object, coacting means between the casing and containers to cause the containers to tilt toward each other by the side impact of the grenade, a flight removable lock for holding the containers against endwise and tilting movement within the casing, and a manually releasable lock for the flight removable lock.

8. In a hand grenade, a casing having two endwise movable and tiltable separated explosive containers enclosed thereby, detonators for the containers, each detonator including a tube open to the interior of its container and to the space

- 5 between the containers, a percussion cap seated in the tube and a firing pin slidable in the tube and projecting into the space between said containers in position to coact with the other firing pin by the end and side impact of the grenade with an object, interior and exterior shoulders on the casing and containers respectively, to cause the containers to tilt toward each other by the side impact of the grenade, and a flight removable lock for holding the containers against endwise and tilting movement within the casing.
- 10 9. In a hand grenade, a casing having two endwise movable and tiltable separated explosive containers enclosed thereby, detonators for the containers, each detonator including a tube open to the interior of its container and to the space between the containers, a percussion cap seated in the tube and a firing pin slidable in the tube and projecting into the space between said containers in position to coact with the other firing pin by the end and side impact of the grenade with an object, interior and exterior shoulders on the casing and channels respectively, to cause the channels to tilt toward each other by the side impact of the grenade, a flight removable lock for holding the containers against endwise and tilting movement within the casing, and a manually releasable lock for the flight removable lock.
